(57) **CLAIM**

We claim the ornamental designs for note sheets and related pads of note sheets, as shown and described.

DESCRIPTION

FIG. 1 is a top perspective view of a note sheet embodying our new design with the note sheet configured to receive indicia and having a rectangular body portion and a rectangular tab portion with rounded shoulders.

FIG. 2 is a bottom perspective view of the note sheet of FIG. 1, the bottom surface having a region of adhesive on the rectangular body portion.

FIG. 3 is a top plan view of the note sheet of FIG. 1.

FIG. 4 is a bottom plan view of the note sheet of FIG. 1.

FIG. 5 is a front-edge elevational view of the note sheet of FIG. 1.

FIG. 6 is a back-edge elevational view of the note sheet of FIG. 1.

FIG. 7 is a left-side elevational view of the note sheet of FIG. 1.

FIG. 8 is a right-side elevational view of the note sheet of FIG. 1.

FIG. 9 is a top perspective view of another note sheet embodying our new design with the note sheet configured to receive indicia and having a rectangular body portion and a rectangular tab portion with rounded shoulders and an overlay.

FIG. 10 is a bottom perspective view of the note sheet of FIG. 9, the bottom surface having a region of adhesive on the rectangular body portion.

FIG. 11 is a top plan view of the note sheet of FIG. 9.

FIG. 12 is a bottom plan view of the note sheet of FIG. 9.

FIG. 13 is a front-edge elevational view of the note sheet of FIG. 9.

FIG. 14 is a back-edge elevational view of the note sheet of FIG. 9.

FIG. 15 is a left-side elevational view of the note sheet of FIG. 9.

FIG. 16 is a right-side elevational view of the note sheet of FIG. 9.

FIG. 17 is a top perspective view of a pad of note sheets including the note sheet of FIG. 9 and a bottom pad carrier sheet.

FIG. 18 is a bottom perspective view of the pad of note sheets of FIG. 17.

FIG. 19 is a top plan view of the pad of note sheets of FIG. 17.

FIG. 20 is a bottom plan view of the pad of note sheets of FIG. 17.

FIG. 21 is a front-edge elevational view of the pad of note sheets of FIG. 17.

FIG. 22 is a back-edge elevational view of the pad of note sheets of FIG. 17.

FIG. 23 is a left-side elevational view of the pad of note sheets of FIG. 17.

FIG. 24 is a right-side elevational view of the pad of note sheets of FIG. 17.

FIG. 25 is a top perspective view of two stacked pads of note sheets wherein each of the two stacked pads of note sheets is the pad of note sheets of FIG. 17 and the pads of note sheets are coupled together with a piece of tape that contacts the bottom surface of each pad of note sheets.

FIG. 26 is a bottom perspective view of the two stacked pads of note sheets of FIG. 25.

FIG. 27 is a top plan view of the two stacked pads of note sheets of FIG. 25.

FIG. 28 is a bottom plan view of the two stacked pads of note sheets of FIG. 25.

FIG. 29 is a front-edge elevational view of the two stacked pads of note sheets of FIG. 25.

FIG. 30 is a back-edge elevational view of the two stacked pads of note sheets of FIG. 25.

FIG. 31 is a left-side elevational view of the two stacked pads of note sheets of FIG. 25.

FIG. 32 is a right-side elevational view of the two stacked pads of note sheets of FIG. 25.

FIG. 33 is a top perspective view of three stacked pads of note sheets wherein each of the three stacked pads of note sheets is the pad of note sheets of FIG. 17 and the pads of note sheets are coupled together with a piece of tape that contacts the bottom surface of each pad of note sheets.

FIG. 34 is a bottom perspective view of the three stacked pads of note sheets of FIG. 33.

FIG. 35 is a top plan view of the three stacked pads of note sheets of FIG. 33.

FIG. 36 is a bottom plan view of the three stacked pads of note sheets of FIG. 33.

FIG. 37 is a front-edge elevational view of the three stacked pads of note sheets of FIG. 33.

FIG. 38 is a back-edge elevational view of the three stacked pads of note sheets of FIG. 33.

FIG. 39 is a left-side elevational view of the three stacked pads of note sheets of FIG. 33.

FIG. 40 is a right-side elevational view of the three stacked pads of note sheets of FIG. 33.

FIG. 41 is a top perspective view of four stacked pads of note sheets wherein each of the four stacked pads of note sheets is the pad of note sheets of FIG. 17 and the pads of note sheets are coupled to a backing card that contacts the bottom surface of each pad of note sheets.

FIG. 42 is a bottom perspective view of the four stacked pads of note sheets of FIG. 41.

FIG. 43 is a top plan view of the four stacked pads of note sheets of FIG. 41.

FIG. 44 is a bottom plan view of the four stacked pads of note sheets of FIG. 41.

FIG. 45 is a left-side elevational view of the four stacked pads of note sheets of FIG. 41.

FIG. 46 is a right-side elevational view of the four stacked pads of note sheets of FIG. 41.

FIG. 47 is a front-edge elevational view of the four stacked pads of note sheets of FIG. 41.

FIG. 48 is a back-edge elevational view of the four stacked pads of note sheets of FIG. 41.

FIG. 49 is a top perspective view of eight stacked pads of note sheets wherein each of the eight stacked pads of note sheets is the pad of note sheets of FIG. 17 and the pads of note sheets are coupled to a perforated backing card that contacts the bottom surface of each pad of note sheets.

FIG. 50 is a bottom perspective view of the eight stacked pads of note sheets of FIG. 49.

FIG. 51 is a top plan view of the eight stacked pads of note sheets of FIG. 49.

FIG. 52 is a bottom plan view of the eight stacked pads of note sheets of FIG. 49.

FIG. 53 is a left-side elevational view of the eight stacked pads of note sheets of FIG. 49.

FIG. 54 is a right-side elevational view of the eight stacked pads of note sheets of FIG. 49.

FIG. 55 is a front-edge elevational view of the eight stacked pads of note sheets of FIG. 49.

FIG. 56 is a back-edge elevational view of the eight stacked pads of note sheets of FIG. 49.
